UNITED STATES PATENT OFFICE.

GEORGE WRIGHT, OF SOUTH ORANGE, NEW JERSEY.

BOAT-LAUNCHING MECHANISM.

Application filed September 24, 1919. Serial No. 326,031.

To all whom it may concern:

Be it known that I, GEORGE WRIGHT, a citizen of the United States, and a resident of South Orange, county of Essex, State of New Jersey, have invented certain new and useful Improvements in Boat-Launching Mechanisms, of which the following is a full, clear, and exact description.

Among the principal objects which the present invention has in view are: to dispose the life boats of a sea going vessel in position to receive their passengers rapidly and automatically; to mechanically dispose the life boats of a sea going vessel in position to receive the passengers in groups of greater or smaller numbers; to actuate mechanisms for launching boats in the manner described from a single station; to adjust the launching mechanism for getting the boats over the side of the vessel or for taking them on the vessel; and to simplify the construction of the mechanism by which the above stated objects are accomplished.

Figures.

Figure 1 is a side view of a mechanism constructed and arranged in accordance with the present invention, the same being shown in the position assumed thereby at the initiation of the launching operation.

Figure 2 is a similar view showing the mechanism and the boat controlled thereby in the position assumed at the end of the operation for taking the boat on board the vessel.

Figure 3 is a vertical section of the boat and elevation of one of the davits for operating the same, the section being taken as on the line 3-3 in Figure 2.

Figure 4 is an elevation of the opposite davit, the view being taken as on the line 4-4 in Figure 2.

Figure 5 is a view showing in reduced scale the section of a fragment of a sea going vessel and mechanism mounted thereon constructed and arranged in accordance with the present invention and in broken lines the active position in two stages of the operation of said mechanism.

Figure 6 is a detail view on enlarged scale showing the swinging arm and fixed pedestal of a davit forming part of the present mechanism, said davit being swung to the active position thereof.

Figure 7 is a detail view in plan showing

the arrangement of the double multiple pulley blocks and cable rove thereon.

Figure 8 is a schematic view showing the electric circuits and electro-mechanical instruments operated thereby.

60

Description.

In the employment of the present invention it is designed to give to the officer in charge of the vessel the opportunity to dispose the life boats of the ship in position to receive the passengers either in groups or all at the same time. Also it is intended that the boats will be arrested at the stations most convenient for receiving passengers and crew. With this in view certain of the mechanisms will have more limited exercise of their functions than others, to the end that certain boats will pass from the boat deck to the promenade deck, others to the main deck and yet others to the wash deck. The boats at all their stations will be secured and controlled by the crew assigned to each boat. The result of this arrangement would be that a great deal of the panic and confusion arising in the event of an emergency at sea from the fact that passengers and crew are compelled to pass from deck to deck by means of constricted or limited passageways or ladders, also to the fact that the crews are interfered with by the passengers and prevented from unshipping the boats as expeditiously as otherwise, would be eliminated. It is obvious that if the boat stations of passengers and crew are assigned with reference to the accessibility of the passengers and crew, the disorders referred to will largely disappear.

With these objects in view the invention embodies davits having booms 15, which are pivoted by bolts 16 on standards 17. The standards 17 are bolted securely to the boat deck, each standard having a foot 18 through which bolts are passed. The bolts 16 are disposed somewhat below the center of the davits. Normally the davits are prevented from swinging on the pivot bolts 16 by blocks 19 against which the lower end or foot of each of the davits rests. The blocks 19 are held in position by suitable springs or counterbalances. In service the davits are rocked to the vertical or inclined position which they assume by the pull of the lifting cables 20 on the pulleys 21 housed in the blocks 22. The blocks 22 are slid-

110

ably mounted on the rectangular ends 23 of the davits 15 and are secured in either of the two positions referred to by the pins 24 when the same are inserted in the holes 25 and 26, the former being disposed above the bolts 16, and the latter below the said bolts. The blocks 22 are so shifted as to accommodate the movement of the boat 27 to which are connected the ends of the cables 20. The boat 27 normally rests in cradles 28, to be lifted therefrom when the cables 20 are drawn upon. The cables 20 are rove around pulleys in the blocks 29 and 30 which are disposed as shown in Figure 7 of the drawings. The blocks 29 are anchored while the blocks 30 move with the cross bar 31. The cross bar 31 has an eyelet 32 which is secured to a cable 33.

The cable 33 is carried to a winch 34 operated when the circuit incorporating the motor attached thereto is closed. As shown in Figure 8 the circuit is closed at the operating station generally on the bridge of the vessel and accessible to the commanding officer. It will be noted that the fixed end of one of the cables 20 is anchored or belayed on the pin 35 which is made fast to the deck of the ship.

When desiring to put the boats overboard it becomes necessary to throw the latch blocks 19 and the saddles 36 of the cradles 28 in which the boat 27 rests. The saddles 36 will pivot on pivot rods 37. The pivot rods 37 have upstanding arms 38 one of which is attached by a line 39 to the pull cable 33. The saddles 36 are inter-connected by the cable 40 while each is operatively connected by cables 41 to the latch blocks 19 adjacent thereto. One of the cables 41 it will be noted is attached to the lower extension of the arm 38, so that when the said arm is rocked with the saddle 36 associated therewith, the latch block 19 connected to the said arm will fall inward in simulation of the movement of the block 19 at the opposite end of the boat.

The upper ends of the davits 15 have bows or heads 42 from which are hung the pulley blocks 43 and through which pass the lifting cables 20. The heads 42 extend in a plane parallel with the keel of the boat. As seen best in Figure 5 of the drawings when the davits 15 are rocked to overhang the sides of the vessel they are supported by the piston rods 44. The piston rods 44 are reciprocally mounted in a dashpot 45, the usual construction and arrangement being provided in the dashpot to regulate the rapidity of movement of the piston rods 44 and of the davits 15 and members associated therewith. At the end of the stroke of the piston 44 in the pot 45 the said piston becomes intermediate support for the davits, as shown in the said Figure 5. It is obvious that although the dashpot offers resistance to the outward fall of the davits 15 the re-

sistance is much modified or totally eliminated when the davit is being drawn in-board, due to the arrangement of valves for controlling the flow of liquid in the dashpot, as is usual in the construction of the same. 70

The normal arrangement of the heads 42 is that shown in Figure 1. In this position the davits will swing outward when the boat 27 is lifted, due to the fact that the pull of the cable 20, as seen in Figure 4, is outward, 75 due to the fact that the said cable extends around the guide pulleys 46 and 47, the former being disposed between the standards 17 and the edge of the deck.

When the officer in charge throws the 80 switch 48 to close the operating circuits controlling one or all of the motors attached to the winches 34, the said winches draw up on the cable 33 to lift the boats 27 directly above the cradles 28. At the same time, 85 through the medium of the line 39 and cables 40 and 41, the saddles 36 and the latch blocks 19 are drawn out of the path of the boat 27, and of the lower end 23 of the davits 15. The outward pull of the cables 20 on the 90 pulleys 21 in the block 22 disposed above the bolts 16 rocks the davits to carry the head 42 thereof beyond the side of the vessel, this movement being regulated by the dashpots 45 and piston rods 44 therein. 95

When the davits 15 have been thrown off of centre, the weight of the boat 27 is sufficient to carry the head 42 of the davits to the outermost positions. When the cable 20 has been wound up by the winch 34 sufficiently to lift and free the boat 27 the operation of the winch is arrested and held by suitable brakes until the davits swing to the full outward position thereof. When the davits swing to the outward position the 100 winches are released to the end that the cable 33 is paid out to release the cables 20 until the boat 27 is dropped to the desired or boat loading position as shown in Figure 5 of the drawings in the upper position indicated by broken lines therein. The automatic control of the boat loading mechanism ceases at this point. As indicated above, the extent to which the cables 20 are paid out before the boat is in the boat loading 110 position depends upon the boat loading position assigned thereto. It will be understood that all of this operation is automatic, resulting upon the closing of the electric circuits for energizing motors connected with winches for pulling the cables 33. When the officers and crew take charge of the boat in the boat loading position the operation of the boats is controlled by an electric circuit and switch contained in the 120 boat and operable by the officer in charge. When the circuit is closed the motor turns the winch to wind the cable 33 and to draw the cables 20 and boats connected therewith upward. When the switch is open the mo-

125
130

5 tor is cut out and an electric brake holds the
winch. By means of an electric circuit the
brake may be released and the winch 34 be
permitted to pay out the cable 33, with the
result that the cables 20 and boats connected
therewith are lowered under control of the
officer in charge. When the boat reaches
the water the cables 20 are released in the
usual manner and the boat draws away from
10 the side of the ship.

In boat drills the boats are returned from
the water by attaching the ends of the cables
20 to the eyes in the ends of the boat pro-
vided therefor. The blocks 22 are shifted
15 from engagement with the holes 25 to en-
gagement with the holes 26. As long as the
weight of the boat and the load carried
thereby is lifted the davits remain in the in-
clined outreaching position. When how-
20 ever the boats are arrested in their upward
travel the drawing effect of the cables 20 on
the pulleys 21 is to rock the davits to the
upright or vertical position, due to the fact
that the blocks 22 are at the lower extrem-
25 ity of the ends 23 of the davit which for the
time extend inward away from the side of
the vessel and from the then position of the
boats.

When the davits 15 have assumed the ver-
30 tical position and the boats 27 are above the
cradles 28, the winches 34 are operated to
lower the boats and the same rest in the
saddles 36 which are moved to the upright
25 position to receive the same. The blocks 19
and parts operatively connected therewith
are then manually disposed in position to
prevent the accidental swing of the dav-
its 15.

40 *Claims.*

1. A mechanism as characterized comprising
a plurality of boat handling mechanisms
each embodying a plurality of suspension
davits, pivots for said davits, a plurality of
45 guide pulleys slidably mounted on said davits
for adjustment at opposite sides of said
pivots, and hoisting cables operatively
mounted on said davits for engaging the
said guide pulleys in adjusted positions.

50 2. A mechanism as characterized comprising
a plurality of boat handling mechanisms
each embodying a plurality of suspension
davits, pivots for said davits, a plurality of
55 guide pulleys slidably mounted on said
davits for adjustment at opposite sides of

said pivots, hoisting davits operatively
mounted on said davits engaging the said
guide pulleys in adjusted positions, and
means for locking said davits in vertical po-
sition. 60

3. A mechanism as characterized comprising
a plurality of boat handling mechanisms
each embodying a plurality of suspension
davits, pivots for said davits, a plurality of
65 guide pulleys slidably mounted on said
davits for adjustment at opposite sides of
said pivots, hoisting cables operatively
mounted on said davits for engaging the
said guide pulleys in adjusted positions,
70 means for locking said davits in vertical po-
sition, and means for releasing said davits,
said means being operable simultaneously
with the hoisting of the lifting cables asso-
ciated with said davits.

4. A mechanism as characterized comprising
a plurality of boat handling mechanisms
each embodying a plurality of suspension
davits, pivots for said davits, a plurality
75 of guide pulleys slidably mounted on
said davits for adjustment at opposite sides
of said pivots; and hoisting cables opera-
tively mounted on said davits for engaging
the said guide pulleys in adjusted positions.

5. A mechanism as characterized comprising,
a plurality of boat handling mechanisms
each embodying a plurality of suspension
davits, pivots for said davits, a plurality
85 of guide pulleys slidably mounted on
said davits for adjustment at opposite sides
of said pivots, hoisting cables operatively
mounted on said davits for engaging the said
guide pulleys in adjusted positions; and
90 means for locking said davits in vertical po-
sition.

6. A mechanism as characterized comprising,
a plurality of boat handling mechanisms
each embodying a plurality of suspension
davits, pivots for said davits, a plurality
95 of guide pulleys slidably mounted on
said davits, for adjustment at opposite sides
of said pivots, hoisting cables operatively
mounted on said davits for engaging the
said guide pulleys in adjusted positions;
100 means for locking said davits in vertical po-
sition; and means for releasing said davits,
said means being operable simultaneously
with the hoisting of the lifting cables asso-
ciated with said davits. 105
